UNITED STATES PATENT OFFICE.

CHARLES R. GALLAGHER, OF LOS ANGELES, CALIFORNIA, ASSIGNOR TO UNIVERSAL HOLDING COMPANY, A CORPORATION OF DELAWARE.

FLOATING-DECK OIL TANK.

Application filed April 20, 1925, Serial No. 24,424. Renewed March 20, 1928.

This invention relates to oil tanks, and more especially to open or uncovered field or storage tanks, and my objects are to provide an efficient bracing means or stiffener for the upper ends of such tanks, an efficient hollow floating deck composed of sections susceptible of ready removal for repair or replacement, the deck having communicating water-collecting chambers and means to conduct the water to the exterior of the tank and at the same time accommodate the deck in its up or down movement responsive to different oil levels in the tank, and having also means to collect and discharge condensation from the air chambers into the water-collecting chambers. Another object is to provide means for supplying oil to the tank and holding the deck against rotary movement and hence any tendency to break or impair the efficiency of the water-discharge means.

With these general objects in view, the invention consists in certain novel and useful features of construction and combinations of parts as hereinafter described and claimed; and in order that it may be fully understood reference is to be had to the accompanying drawings, in which:

Figure 1 is a broken side elevation of an oil tank embodying the invention.

Figure 2 is a top plan view of the tank.

Figure 3 is an enlarged central radial section of a fragment of the floating deck.

Figure 4 is a transverse section taken through four of the segmental sections of the floating deck, said figure being shown on a scale of twice the size of Figure 3.

Figure 5 is a greatly magnified fragmental section on the line V—V of Figure 3.

Figure 6 is a fragmental vertical section taken through the tank and deck in the plane of the filling tube of the tank.

Figure 7 is a vertical section of a modified form of interlock connection at the lower meeting edges of the deck sections.

Figure 8 is a vertical section of a telescopic water-drain for the deck sections.

Referring to the drawings in detail, 1 indicates an ordinary circular oil tank of the conventional uncovered type, and projecting from the upper flanged end of the tank are lugs 2, through which extend take-up or turn-buckle rods 3. The rods extend ra-

dially and are attached at their inner ends to a central plate 4 and at their outer ends are engaged by clamping nuts 5. At suitable points the rods are provided with turn-buckles 6 for take-up purposes. 7 is an oil supply pipe extending over and vertically downward in the tank and secured at its lower end to a socket 8, being provided near such end with a cross coupling 9 for discharging oil into the tank.

A floating deck consists of a series of segmental sections 10 abutting together side-wise and at their inner ends, against a central water-collecting tube 11. Each section is provided with superposed air and water chambers 12 and 13 respectively, the water chambers being uncovered. Through the side walls of the water chambers of the abutting sections, tubular fasteners 15 extend. Similar tubular fasteners 16 extend through the inner end walls of the water chambers and the central tube 11, and provide a means for the escape of water from said chambers into said tube. Cooperating with the tubular fasteners 15 and 16 in securing the segmental sections of the deck together, are interlocking parts at the bottom of the deck, these parts consisting of depending radial ribs 10^a, and depending radial upwardly-facing hooks 10^b, the radial ribs 10^a occurring at the sides of alternate sections and fitting in the radial hooks of the interposed sections. By this arrangement it will be seen that any one of the sections provided with the depending radial ribs can be readily removed for repair or replacement, and that to effect the removal of one of the sections provided with the radial hooks, it will be necessary to first remove the two flanking segments provided with the radial ribs, it being of course understood that the cooperating tubular fasteners 15 and 16 must likewise be removed. If preferred the depending parts 10^a may be of single thickness and the hooks 10^b of like character, instead of having each of such parts of double thickness as shown in Figure 4. An equivalent construction appears in Figure 7 where adjacent sections have depending pins 11^c and perforated plates 10^d, respectively, the plates underlying the pin-carrying sections and receiving the pins 10^e of the latter in their perforations. The sec-

tional constructions of the deck, as described, not only provide for convenient and inexpensive repair and replacement but facilitates the handling, shipping and storing of the sections of the deck.

To conduct rain water and the like collecting in the water chamber of the deck above the level of the tubular fasteners 16, a telescopic tube 17, extends downward from and 10 communicates with the tube 11, and extends at its lower end through the bottom of the tank, and to discharge exteriorly thereto, a tube 17^a extends from the bottom member 15 of the telescopic tube to the exterior of the tank, and is controlled by a valve 18. The tube sections 17 are so proportioned that they shall accommodate the deck when it attains its highest level, that is when the deck is floating on a full charge of oil in 20 the tank, and shall be fully nested when the deck is depressed to its greatest extent, as when the tank is practically empty.

To relieve this telescopic tube of twisting strain due to rotary or oscillatory movement 25 of the deck, the latter is provided with an opening 19 through which the filling tube 7 extends. This arrangement obviously restrains the deck from rotary or like movement. The joints between the sections of 30 the telescopic tube are made water-tight by packing glands 19^a.

As the functions of the various parts have been explained no recapitulation of the entire operation is deemed necessary, it being 35 understood of course that because of the tubular connections 15, rain water collecting in the deck will be evenly distributed there-over and can find its way through any or all of the tubular fasteners 16 into the tube 40 11 and thence through tube 17 to the exterior of the tank.

As the air chambers 12 will sometimes be charged with water of condensation, an 45 automatic pump or breather for such water is provided, as follows: Each air section 12 is formed with a slight depression or well 20 into which all water received in the chamber will collect. Secured fixedly and in air 50 tight relation to the bottom of the water chamber 13 is a short pipe section 21 having its lower end received within the well 20 and having its upper end down-turned as at 22 for excluding rain water. When the well 20 is filled, movements of the walls or 55 the air chambers due to expansion or contraction as a result of varying temperature, or the like, effectually results in the expulsion of water through the pipe 21 into the superposed water chamber 13.

60 From the above description it will be apparent that I have produced an oil tank embodying the features of construction set forth as desirable in the statement of the objects of the invention, and which is obviously susceptible of modification in minor 65

particulars without departing from the principle of construction involved or the spirit and scope of the appended claims.

What I claim is:

1. The combination of an oil tank, a floating deck therein having a water-collecting chamber, a telescopic water tube extending downward from the said chamber, a tube leading from the telescopic tube to a point exterior to the tank, and a filling pipe leading into the tank through the deck and adapted for preventing rotary movement thereof. 70

2. A deck having superposed air and water chambers and provided at the bottom 80 of the air chamber with a depression for the reception of water of condensation, and a breather pipe rigid with the deck and disposed at its lower end in the depression and above the water chamber with a down-turned end for discharging into the water chamber. 85

3. A deck having superposed air and water chambers and provided at the bottom 90 of the air chamber with a depression for the reception of water of condensation, and a breather pipe rigid with the deck and disposed at its lower end in the depression and above the water chamber with a down-turned end for discharging into the water 95 chamber, in combination with a tank containing the deck, and a telescopic tube communicating at its upper end with the water chamber, and a tube leading from the lower end of the telescopic tube to the exterior of 100 the tank.

4. A deck for oil tanks, composed of a circular series of sidewise-abutting segmental sections having communicating water-collecting chambers, tubular fasteners extending through the abutting walls of the said sections for establishing communication between the water chambers thereof, a central tube surrounded by said sections, tubular fasteners connecting the tube with the inner walls of the said sections for the passage of water from the water chambers of the latter into said tube, and a telescopic tube for conducting water from the said central tube. 110 115

5. A floating deck for oil tanks, comprising a circular series of sidewise-abutting segmental sections having superposed air and water chambers, the adjacent sections having interengaging bottom elements inhibiting independent lateral movement of the sections but permitting separating vertical movement of the latter. 120

6. A floating deck for oil tanks, comprising a circular series of sidewise-abutting segmental sections having superposed air and water chambers, alternate sections having depending radial ribs and the interposed sections having depending hooks receiving such ribs. 125 130

7. A floating deck for oil tanks, comprising a circular series of sidewise-abutting segmental sections having superposed air and water chambers, alternate sections having depending radial ribs and the interposed sections having depending hooks receiving such ribs, and a tube fitting between the inner ends of the sections and secured thereto and communicating therewith.
8. A floating deck for oil tanks, comprising a circular series of side-wise abutting
- sector sections having superposed air and water chambers, and means for attaching the sector sections together, said means including tubular fasteners providing a conduit for the passage of water from the water chambers of each sector section to its adjacent sector section. 15

In witness whereof I hereunto affix my signature.

CHARLES R. GALLAGHER.
